DANIEL WOODBURY, OF ROCHESTER, NEW YORK.

Letters Patent No. 89,368, dated April 27, 1869.

IMPROVEMENT IN HORSE-POWER.

The Schedule referred to in these Letters Patent and making part of the same.

To all whom it may concern:

Be it known that I, DANIEL WOODBURY, of the city of Rochester, in the State of New York, have invented a new and useful Horse-Power; and I do hereby declare that the following is a full, clear, and exact description thereof, reference being had to the accompanying drawing, making part of this specification, in which—

Figure 1 is a top view.

Figure 2 is a side elevation, with a portion (bull-wheel D) broken away.

Figure 3 is a view of the receiving-openings of main frame E for girder H.

Figure 4 is a perspective view of the end of lever h^2 and standards y and y^1 .

Figure 5 is a longitudinal section of the end of lever h^2 , plate y^6 , showing the arrangement of hook x^4 .

Figure 6 is an inverted view of plate y^6 with the lever h^2 removed.

Figure 7 is a vertical section of spur-wheel L.

Figure 8 is a vertical section of pinion 3.

The nature of this invention will be understood from the drawings and specifications.

To enable others skilled in the art to make and use my invention, I will describe its construction and operation.

On the axle A, figs. 1 and 2, I place two standards B, fig. 2, which carry the frame of this machine. The standards have tenons on each end, which enter mortises extending partially through the frame and axle, the whole being bound together by clamping-bolts passed through the frame and axle.

The frame consists of a longitudinal wooden beam, C, figs. 1 and 2, of sufficient length to allow the bull-wheel D to rest thereon.

Across this beam, I place two cross-girders H, fig. 1, which at one end are attached to the bridge-tree G of circular frame E, by the ends entering such an opening as shown in fig. 3. The other ends of girders H are bound and held by a metal frame having the same receiving-openings, the whole being bound together by clamp-bolts extending from the outside of the bridge-tree G to the outside of the metal frame on the other end of girders H.

The circular iron frame E is in diameter less than the bull-wheel D, and attached at both ends to the beam C, figs. 1 and 2, by bolts.

Across this frame, and near its outer circumference, the bridge-tree G is formed, which receives the ends of girders H.

In the outer rim of the frame E there is a vertical slot which receives the journal-boxes f, figs. 1 and 2, of shaft x, fig. 2.

This box f is a pipe-box, and made in one piece, and held in its place by a cap, a, figs. 1 and 2, which is held by bolts b extending from lugs a', fig. 2, on the frame E, having centre-heads immediately below the lugs.

Below the bull-wheel D, I put a cog-wheel 3, fig. 2, that forms a support for it.

This cog-wheel 3 is on a stud 4, fixed to and extending through the plate 6, which is also sustained by the bolts b, below the lugs a'.

The bolts b have on their lower ends a wood-washer, 7, fig. 2, so that if any hard substance should get between the pinion e, fig. 2, and the bull-wheel D, they will yield, and prevent the bevel-wheel L from getting out of gear with the pinion e, fig. 2, and breaking it.

The opposite end of the shaft x has similar journal-boxes resting in slots in the iron frame that connects the other ends of the girders H. The bull-wheel D and pinions e, driven by it, are constructed and operate the same as set forth in my patent dated 18th August, 1857.

On the pinion-shaft x, I key a spur-wheel, L, figs. 1, 2, and 7, which runs between the bridge-tree G and the outside rim of frame E.

The hub f^2 of bevel-wheel L is made detachable from the wheel, and bolted thereto, as shown in fig. 7. That portion of the wheel is left open.

This opening also extends out nearly to the rim, as shown at x^3 , fig. 2, and is sufficiently large at the outside to allow the hub to pass through when it is detached and moved out towards the periphery of the wheel.

By this arrangement, when the windlass K is not on the machine, by detaching the hub f^2 , and turning the wheel down so the hub will pass through the opening, the wheel will lie flatwise on top of the machine, and take less room in packing.

The bevel-wheel L is keyed to shaft x, and gears into and drives a pinion, e, on the tumbling-rod c³, fig. 1.

The pinion 3 has a hollow space on the inside for oil, and an oil-hole leads thereto from the outside, as shown in fig. 8.

The rod c³ is sustained at one end in boxes 8, fig. 2, attached to hangers P, and passes through a box, P², on the plate G² of sustaining-brace P³, fig. 1.

On the ends of the girders H, I place journal-bearings F and F', fig. 1.

These bearings carry the windlass K.

On one end of the shaft of the windlass K there is a spur-wheel, O, fig. 1, which gears into a pinion on the shaft x, by which it is driven, thereby imparting motion to the windlass when desired.

On the opposite end of the windlass, another wheel may be placed, between which and a pinion on shaft x, a counter-shaft and pinion can be placed, which, being put in gear while the first is out, will reverse the motion of the windlass.

On the rim of the bull-wheel D, I attach two standards y and y¹, figs. 1 and 4, which receive between them a clamping-bolt h of the lever h², figs. 1 and 4.

This bolt is attached to a strap that is fitted to the end of the lever h², as shown in fig. 4.

The bolt h being vertically adjustable between the standards y and y' , the outer end of the lever is vertically adjusted, thereby suiting it to the draught of the horses.

On the lever h^2 , near the inner end, there are pivoted jaws h^3 , fig. 1, that receive the end of a lug, a^4 , fig. 1, on the bull-wheel D . This forms a fulcrum on which the lever h^2 rests, and the ends move vertically.

A brace, k^2 , also extends from near the centre of the lever h^2 to the bull-wheel.

It is attached to the lever by passing a bolt through the metal eyes on the brace and the staple in the lever, and to the bull-wheel by a hook, x^4 , figs. 5 and 6, that enters an eye on a lug on the rim of the bull-wheel.

This hook is attached to the brace k^2 by having its inner end bent, as shown in fig. 6, to receive a bolt, x^6 , which also holds a metal plate, y^6 , thereon, and clamps the whole together.

By this arrangement, if a hook breaks it is easily detached to be replaced by another.

To the rear and front ends of beam C , I attach an eye, y^7 , figs. 1 and 2, which receives one end of the sustaining-braces P^3 , fig. 1. The front brace is partially broken away in the figure. The right-hand brace, when in position, passes through the wheel, as shown in fig. 1.

The outer ends of these braces P^3 are fastened to an arm of a metal plate, G^2 , fig. 1.

This plate G^2 has also another arm, with a hook formed on its end, as shown in fig. 1.

From this hook there extends to a hook, p^3 , on the beam C , figs. 1 and 2, a rod H^2 , fig. 1, which is longitudinally adjustable by a swivel-joint and screw, so that when the plate G^2 , with the brace P^3 is staked to the ground, by operating the swivel-joint, a strain can be got that will hold the machine steady.

Near the back end of the beam C , and to the under side, I pivot a tongue, J^3 . This serves to draw the machine by, and when the out end rests on the ground, the bull-wheel D can be levelled from it.

The rack k^3 , fig. 2, is attached to the front and under side of beam C , and gears into a pinion in the tongue J^3 , on shaft S , fig. 2.

On this shaft S there is a ratchet-wheel, R , figs. 1 and 2, which is held in any desired position by a pawl, R^2 , attached to the tongue, J^3 , fig. 2.

This wheel R can be turned by handles f .

By raising up the pawl and turning the wheel R , it operates the rack k^3 , thereby elevating or depressing the bull-wheel D , when the tongue rests on the ground.

To the frame E , and the cross-frame on the opposite ends of the girders H , I rigidly attach metal lugs g and g' , fig. 1, which serve to keep the bull-wheel in its place, and may also serve as seats for friction-rollers operating on the rim of the bull-wheel, as shown in my patent dated 18th August, 1857.

On the beam C , I bolt a step S^6 , to receive the lower end of one of the legs of a derrick, when used in connection with this machine.

On the side of the tongue J^3 , I pivot a sheave, T ,

fig. 1, around which the rope runs when the windlass k is used, and is advantageous for many purposes, in connection with the windlass.

The frame E may be made so as to extend to the beam C , or only to the outside of girders H , and braces put between the girders and the ends of the beam to stay the frame.

The machinery and frame of this horse-power are located sufficiently forward of the axle A to allow the wheels to come near enough together to track with a common wagon, which is a great advantage in passing over a roadway, and being thus located it also throws the weight on the tongue J^3 , which I prefer.

The wheel L is bevelled, so that a drum-shaft may be driven from the top, and be parallel to the frame of the machine, instead of inclined, as the shaft x , so that a belt could be used in place of the tumbling-rod e^2 .

What I claim as my invention, and desire to secure by Letters Patent, is—

1. The metal frame E , with its legs 20, or their equivalents, and bridge-tree G , in combination with girders H and beam C , for the purpose of making a compact support for the machinery of horse-powers of this class.

2. The lugs g and g' , in combination with the bull-wheel D , as and for the purpose set forth.

3. The sustaining-braces P^3 , connecting-plate G^2 , and straining-rod H^2 , in combination with the main frame of this class of horse-powers, as herein described, and for the purpose set forth.

4. Standards y and y' , in combination with the lever h^2 , for the purpose set forth.

5. The hook x^4 , when constructed as herein shown, in combination with plate y^6 and bolt x^6 , all acting conjointly for the purpose specified.

6. The bevel-wheel L , having a detachable hub f^2 , for the purpose set forth.

7. The pinion 3, when constructed with a cavity around the eye, as herein described, and for the purpose set forth.

8. The pivoted tongue J^3 , in combination with the elevating-devices, substantially as described.

9. The pipe-box f , when constructed in one piece, in combination with its cast seats, of main frame E , substantially as and for the purpose set forth.

10. The step S^6 , in combination with the main frame of this class of horse-powers, as and for the purpose set forth.

11. The eye y^7 , hook p^3 , and beam C , in combination with the rod H^2 and sustaining-brace P^3 , as and for the purpose set forth.

12. Attaching and supporting the main frame of horse-powers of this class on the axle, by means of standards B , braces 22, and holding them together by clamping-bolts 21, as herein shown and described.

DANIEL WOODBURY.
